INSUFFLATION CANNULA

Ernest Myller, New York, N. Y.

Application December 30, 1947, Serial No. 794,518

2 Claims. (Cl. 128—2)

1 My invention relates to an improved cannula and more particularly to an insufflation cannula especially adapted for introduction in the cervical canal of the uterus.

The object of this invention is to provide a device of this kind consisting of a combination adapted to be used for different medical purposes.

More particularly the new device according to my invention is useful for carrying out the Rubin test, as well as hysterosalpingography.

As known to those skilled in the medical art, the Rubin test consists of testing the permeability of the oviducts by means of blowing air or carbon dioxide through the external os, after an air-tight closure of the cervix has been accomplished. A manometer indicates whether the tubes are open or closed.

Hysterosalpingography consists of filling the tubes and the uterus with a contrast medium for the purpose of using X-rays to determine whether the tubes are open or closed, and to visualize the contours of the uterus.

Other objects, novel features and advantages of my invention will become apparent from the following specification and accompanying drawing, wherein one embodiment of my invention is shown.

In the drawings:

Figure 1 is a perspective view of a cannula embodying the invention.

Fig. 2 is a front view of part of the instrument according to Fig. 1, partly broken.

Fig. 3 is a longitudinal section of the lower part of the instrument on an enlarged scale, presenting an interchangeable tip.

Fig. 4 shows a modified form of the interchangeable tip according to Fig. 3.

Fig. 5 is a side view of the part shown in Fig. 2, partly in section.

Fig. 6 is a detail showing the provision of an inflatable tubing on the instrument.

Fig. 7 shows the same detail as Fig. 6, the tube being inflated.

Figs. 8, 9, 10 and 11 are sections through line 8—8 of Fig. 1, showing a three-way cock provided in this part of the instrument, in different positions.

Referring to said drawings, the improved instrument comprises an external tubular member 1, the size and shape being that of a regular uterine sound. Inside, two tubes 3 and 4 are provided. Tube 3 is provided with a lateral outlet 5 somewhat below its closed upper end 6, which corresponds to a lateral outlet on tube 1. Tube 4 extends somewhat above tube 3. It is provided at

its upper end with means for inserting an interchangeable tip, for instance, with a thread 7.

A short tip 8 for intra-cervical use is shown in Fig. 3. A longer tip 9 for insertion in the uterine cavity is shown in Fig. 4. At the top of the tips a plurality of openings 10 is provided.

Near its lower end, member 1 is enclosed by a jacket 12, composed of an elastic material, such as rubber, coagulated latex, etc., said jacket covering opening 5. The rubber jacket is held in position on the tube 1 by means of threads 13. By pressing air through tube 3 the jacket 12 can be dilated to form a balloon adapted to accomplish an air-tight closure of the external opening of the cervix when the sleeve is inserted in the cervical canal (see Figs. 1 and 7).

In order to make the new device useable for different purposes, distributing means are provided at the upper part of the instrument.

20 These means comprise a three-way valve 14 which is provided in the center of a casing 15. Said casing is arranged on the top of the tubular member 1 which surrounds the main parts of the tubes 3 and 4. The casing encloses the upper 25 parts of said tubes 3 and 4 extending from said tubular member 1.

Tube 4 is arranged in the center of casing 15, its upper open end leading to the center of valve 14. Tube 3 leads to the top of casing 15. It is 30 plugged and thereby closed by a screw 15' provided at the top of casing 15. Tube 3 is situated to touch tangentially the side of valve 14. Tube 3 is closed at the top and an opening 16 is provided at the point of contact between valve and tube.

35 A short tube or hub 17 is centrally placed at the top of casing 15, providing a connection between the casing and the outside of said tube 17, and positioned in line with the part of tube 4 which is inserted in the casing.

40 A connecting hub 18, similar to hub 17, is provided at the lower right side of casing 15. A tube 19 arranged at an angle of 45° to the side face of the casing connects said hub 18 with the valve 14.

The valve 14 is controlled by a dial knob 28 which is arranged outside the casing and attached to valve 14. The whole valve assembly is fixed in the casing and held together by washer 20 and screw 20'.

50 Means are provided for indexing the different positions of the three-way valve, thus assuring correct alignment with the various conduits in the casing. One embodiment of the indexing and aligning device is shown in Fig. 2, and a modification in Fig. 5.

As shown in Fig. 2, cavities 21 are provided on the outside rim of knob 28 in appropriate positions. A plate with an elastic tongue 22 is held in position above knob 28 by hub 17. Tongue 22 is provided with a spherical rivet 23 which is pressed against the rim of knob 28. When this knob is turned around the rivet 23 will engage the different cavities 21 which correspond to dial marks provided on the outside of knob 28, thereby indicating the actual position of the valve.

In the modification shown in Fig. 5, cavities 24 are provided on the lower side of dial knob 28, corresponding to the marks of the dial. When the knob is turned around a spring loaded ball 25 provided in the casing engages one of said cavities 24 and fixes the knob and indicates the position of the valve. The described means makes it possible to use the instrument in not too bright light, for instance, in the X-ray room, since the change of position of the three-way valve effected by turning the dial can be felt by the operator.

Various instruments can be adapted to the different connections leading to the inner side of the casing. A syringe 26 may be connected, for instance, with the instrument through hub 17. A manometer 27 may be attached to hub 18.

Different possibilities for using the new instrument will become apparent from the following description of its application.

As shown in Figs. 1 and 2, the dial indicates four possible positions of the three-way cock, namely, "B," "C," "X," and "R."

Position "B" is shown in Fig. 8. In this position a direct connection is provided between hub 17, to which syringe 26 may be attached, and tube 3 leading to rubber sleeve 12, which can now be dilated to form a balloon closing the external opening of the cervix.

Position "C" of the cock is shown in Fig. 9. In this position the device is closed. There is no connection from the outside with any of the conduits provided in the casing.

Position "X" of the cock is shown in Fig. 10. In this case hub 17 is directly connected with tube 4, thus forming a straight connection from the syringe to the uterus. This position is used for injection of contrast mediums for examination by X-rays, or salpingography.

Position "R" of the valve is shown in Fig. 11. In this case tube 4 leading to the uterus is connected with hub 17. There is also a connection between hub 18 and tube 4. This is the position for carrying out the Rubin test. To accomplish this a 20 cc. syringe is attached to hub 17 and an ordinary manometer to hub 18.

In using the new insufflation cannula according to my invention the device is first placed within the cervical canal whereupon the balloon is inflated. This may be performed by providing a direct connection between hub 17 to which syringe 26 is attached and tube 3 leading to the rubber jacket 12, as shown in Fig. 8, (position B) and by injecting water with said syringe into said jacket. The inflated balloon holds the cannula firmly in place. No other mechanical devices or tenaculas are necessary.

The device is hereafter brought into position C, shown in Fig. 9, thereby cutting off any outside connections.

In order to carry out utero-salpingography, the disk 28 is turned into position "X" (Fig. 10) thereby forming a direct connection between hub 17 and tube 4.

The X-ray contrast medium is injected with a Luer syringe through hub 17. In case fractional

injection of the contrast medium is preferred the valve 14 is moved into position "C" (Fig. 9) by turning disk 28 accordingly thereby closing the device between the different injections.

To carry out the Rubin-test valve 14 is brought into position "R" (Fig. 11) by turning disk 28 accordingly. A 10 or 20 cc. Luer syringe filled with air or CO₂ is attached to hub 17 and a manometer 27 is attached to hub 18.

In case the Rubin test is to be made with Kymographic equipment position "X" is used. In this case the tube of the Kymograph must be attached to hub 17.

Among the advantages of this instrument over others are its simple use, the air-tight closure of the cervical canal, atraumatic application and painless use. Another advantage which will be apparent to the medical profession is that with this instrument there will be no change in the position of the uterus during the test.

The foregoing description and drawing describe the instrument in what I consider a preferable form, but it will of course be understood that the instrument may be varied without altering the principle of the invention.

Such changes may be made as desired which fall within the scope of the appended claims.

I claim:

1. An insufflation cannula usable for different medical purposes comprising an elongated tubular body of the size and shape of a regular uterine sound, said body surrounding two conduits, one of said conduits leading to an exchangeable tip provided at the outer end of said tubular body, the other one having a lateral outlet corresponding to a lateral outlet provided on said tubular body; an elastic, inflatable sleeve surrounding said outlets and a distributor provided at the top of said body comprising two hubs leading out of the instrument, and a three-way cock adapted either to close the instrument or to connect each of said tubes with said hubs, one of said hubs being adapted to be connected with means for filling the Fallopian tubes and the uterus with a contrast medium for X-ray examination and with means for testing the permeability of the oviducts, respectively.

2. In a device as defined in claim 1, a casing surrounding the upper part of the conduits and a three-way cock engaging said conduits; a dial knob connected with the three-way cock and arranged outside said casing, and means provided partly on said dial knob and partly on said casing and adapted to fix the three-way cock in any desired position.
